UNITED STATES PATENT OFFICE.

ISAAC F. BURTON, DECEASED, LATE OF PHILADELPHIA, PENNSYLVANIA, BY MANIE E. BURTON, EXECUTRIX, OF PHILADELPHIA, PENNSYLVANIA, ASSIGNOR TO VISUAL-ATONE COMPANY OF AMERICA, OF PHILADELPHIA, PENNSYLVANIA, A CORPORATION OF DELAWARE.

GOVERNOR AND GOVERNOR STOP.

Application filed May 21, 1924. Serial No. 714,789.

My invention relates to operating mechanism of talking machines and more particularly to mechanism for speed control and for starting and stopping the turntable.

5 The main purpose of my invention is to provide mechanism for automatic and hand control of the operation of the turntable at once well adapted to the needs of service and easy and inexpensive to manufacture.

10 A further purpose is to have setting and trip lever mechanism for starting and stopping the turntable brake upon the governor disc instead of upon the turntable, as has hitherto been customary, thereby obtaining 15 easier braking and relief from starting and stopping strains in the mechanism between the governor and turntable.

A further purpose is to provide the speed 20 regulator lever with an adjustable scale pivoted upon the pivot of the regulator lever.

A further purpose is to support both ends 25 of the springs of a spring and ball type of speed governor from turning with respect to the governor shaft, thus dividing and reducing torsional stresses upon the springs.

A further purpose is to provide direct as 30 distinguished from derived balance of a horizontal spring and ball speed governor by placing the spring and ball units directly opposite each other.

A further purpose is to further reduce torsional stresses upon the springs by flattening the balls and fastening to the springs at a flattened portion, bringing the center of mass 35 of the balls nearer to the fastening of the springs.

Further purposes will appear in the specification and in the claims.

I have preferred to illustrate but one of 40 the various forms of my invention, selecting a form which has proved to be practical, efficient and reliable and which at the same time well illustrates the principles involved.

45 Figure 1 is a horizontal section above the turntable of a talking machine equipped with my invention.

Figure 2 is an enlarged fragmentary top plan view of the structure of Figure 1 with the turntable and tonearm removed to disclose operating details.

50 Figure 3 is a detail section taken upon the line 2—2 of Figure 2.

Figure 4 is a fragmentary top plan view showing a portion of Figure 2.

Figure 5 is a side elevation of Figure 4. 55

Figure 6 is a detail section of the governor taken upon the line 6—6 of Figure 4.

Like numerals refer to like parts in all figures.

Describing in illustration and not in limitation and referring to the drawings:—

Prior to my invention talking machines have been operated with starting and set automatic stop mechanism and automatic speed governing that has worked fairly well but 65 which has had disadvantages which it is my aim to correct.

The speed governor has been of the centrifugal horizontal spring and ball type having three spring-and-ball units spaced at 70 120°, the springs being fastened at one end to a fixed collar on the driving shaft and at the other to a loose collar carrying the friction disc for speed regulation and the breaking for set automatic stopping has been 75 against the turntable itself.

I have discovered that disadvantageous stresses in the springs of the spring-and-ball units with accompanying imperfect balancing of these units may be considerably reduced by locking the loose collar from any turning with respect to the shaft upon which it is mounted and along which it is adapted to slide, thus supporting both ends of the springs against rotary movement with respect to the shaft; that these stresses and imperfect balancing may be further reduced by directly balancing one spring-and-ball unit against another directly across the center, getting additional advantage from the increased number and still further reducing the imperfect balancing by flattening the balls to move their centers of mass nearer to the springs. 90

I have further discovered that disadvantageous stresses in the operating mechanism between the governor shaft and turntable may be reduced and braking to stop the turntable made more easy by braking against the friction disc of the governor instead of 100 directly against the turntable.

In the figures the mechanism to which my invention is applied is shown to a considerable extent conventionally.

I show conventionally sound box 10, having a needle 11, turntable 12, a tone-arm 13, horn 14 and doors 15 of the cabinet 16.

The turntable spaced above the top plate 17 is mounted upon a vertical shaft 18 that passing through the top plate carries a wormwheel 19 meshing with worm 20 upon the driving shaft 21, driven by any suitable motor 22 and carrying centrifugal spring-and-ball friction-disc speed governor 23.

The spring-and-ball units 24 are balanced directly by placing each unit directly across the center from its balancing unit (see Figure 6) and the balls 25 are flattened as shown to bring their centers of mass closer to the springs and to reduce to a minimum fanning of the air from the rapid revolution of the balls. The curvature of the outer surfaces of the balls is such as to conform approximately with the curves generated by their revolution at usual speeds.

The balls may be fastened to the springs 26 in any suitable manner, as by screws 27.

The springs are fastened at one end each by screws 28 to the collar 29 rigidly secured to the driving shaft 21, and at the other end are fastened by screws 28' to the sliding collar 30, mounted to slide on the shaft responsive to centrifugal action of the balls but locked from turning with respect to the shaft, in order to support the springs against torsion at both ends.

This locking of the sliding collar 30 is conveniently effected by engagement of intersliding portions 31 and 32 of the respective collars, which portions, for better balance are preferably complementary and semi-cylindrical, as best seen in Figures 4 and 6.

The friction disc 33 is rigidly mounted upon the sliding collar 30, and is located somewhat below the metal top-plate 17 and motor board 34, as best seen in Figure 5.

The brake element 35 for speed control is mounted at the end of a downwardly projecting arm 36 of the bell-crank member 37 pivoted at 38 upon the upper side of the top-plate, the top-plate and motor board being suitably cut away at 39 and 40 to pass the arm 36.

The bell-crank member 37 comprises the speed regulating lever. Its outer end is conveniently bent upward at 42 to form a handle and near the handle is perforated and shaped to an indicating point 43. An adjustable graduated plate 44 beneath the perforation at 43 provides visual indication of the speed. The graduated plate 44 is preferably provided with an inwardly extending arm 45 pivoted on the bell-crank pivot 38. Its outer end is bent up to a handle 46 similar to the handle 42 of the bell-crank member.

The pivot screw 38 is of standard type shouldered at the threaded portion 47 which screws into the top-plate. A forked spring

washer 48 is compressed between the bell-crank and scale member and is held to place by means of a screw 49 passing through the rearwardly projecting arm 50 of the washer and into the top plate. It provides friction 70 at the pivot 38 sufficient to maintain these members in place wherever set, yet not enough to prevent setting. The friction upon the bell crank member is much less than that upon the scale member, avoiding 75 danger of any setting of the bell crank member effecting displacement of the scale.

With the speed regulator and regulator scale arms in the position shown in the figures, the handle 46 of the scale arm is moved (both arms moving together) until normal speed is obtained at the record disc, as 78 to 80 revolutions per minute; after which the scale arm is not again disturbed, the speed regulator arm handle 42 being moved toward 85 "S" or "F" when it is desired to have the record run abnormally slow or abnormally fast respectively, such adjustment of the speed regulator arm not affecting the position of the scale.

The mechanism shown for setting the machine to automatically stop the disc when a record has been played through is much of it conventional and old, the principal advantageous new feature here being that of braking against the governor disc 33, which revolves at perhaps 1200 revolutions per minute, instead of against the record disc, revolving at 78 to 80 revolutions per minute.

The brake lever 51, operative automatically or by hand, is generally similar to the speed regulator lever in that it comprises a bell crank member pivoted above the top plate and having a downwardly projecting arm 37' carrying at its lower end a brake element 36' to engage the friction disc 33 of the governor.

The brake lever is loosely pivoted upon the screw pivot 52 which screws into the top plate, the spacing washer 53 maintaining 110 the lever somewhat above the top plate. The lever is resiliently pulled toward braking and stopping of the disc 33 and the driving shaft 21 by the tension spring 54 between lugs 55 and 56 respectively on the brake lever 115 and on the trip latch arm 57.

The trip arm is mounted upon a hub member 58 loosely pivoted upon the shouldered screw 59 secured within the top plate, and is provided with an offset toe 60 adapted to latch in the notch 61 in an arcuate portion 62 of the brake lever. When the toe of the trip arm is latched in the notch of the brake lever, the lever is positioned so as not to brake upon the disc 33, but when the toe is released from its notch, either automatically or by hand, the brake lever is pulled by the spring 54 causing the lever to brake against the disc 33, stopping the disc.

The V-setting member 63, for automatic 130

stripping of the latch at the end of a record, is frictionally mounted and pivoted upon the hub 58 to frictionally grip the latch member, a fibre friction washer 64 being placed between the two members, and the spring washer 65 pressing the V-member down.

The hub member 58 may or may not be rigidly fastened to the latch arm. It is shown widely flanged above its bearing boss to afford wide contact with the latch member and its upper end is flanged at 66 to hold in place the forked spring washer 65.

The friction between the V member 63 and latch member 57 is sufficient to let the V member open the latch but not so great as to prevent different settings of the V member with respect to the latch.

Automatic tripping of the latch is effected by providing a downwardly projecting arm 67 from the tone arm to engage the trip end 68 of the V member. The setting operation is usually the following:

While the turntable is stationary and the toe of the trip arm out of the notch of the brake arm, in the position of Figure 2, the brake 36' engaging the disc 33, the record is set in place on the turntable and the needle of the tone arm is set in the last groove of the record. The V member is then moved by the handle 69 until the trip end 68 engages the arm 67 from the tone arm; the tone arm is then lifted and the needle is set in the first groove. The brake upon the friction disc is next released by latching the toe into the notch at the brake lever handle 70, the latching motion of the latch arm giving corresponding slight motion to the V member, bringing the trip end in proper position to be engaged by the arm of the tone arm before the last groove has been reached and to release the latch to stop the turntable at the end of the record. The V and trip-latch members are not in themselves new and other forms of hand and automatic brake operation could be used.

The motor 22 is of any suitable type, either spring or electric. If the motor be of the electrical type it is desirable to have the motor free from current whenever the turntable is not going. Obviously this may be done by having the electric circuit through the motor turned on when in latching brake position and off at other times. This has been shown diagrammatically in Figure 2, where spaced contacts 71 and 72 in the motor circuit are connected electrically by a spring member 73 when the brake arm is in latching position and not so connected when the brake arm is in braking position. The spring member is shown mounted upon the brake arm.

In view of my invention and disclosure variations and modifications to meet individual whim or particular need will doubtless become evident to others skilled in the

art and it is my wish to claim all such in so far as they fall within the reasonable spirit and scope of my invention.

Having thus described my invention, what I claim as new and desire to secure by Letters Patent is:—

1. In the operating mechanism of a talking machine, a speed governor having a friction disc, a brake therefor embodying a pivoted bell-crank lever, and means for automatically applying the brake at the end of a record. 75

2. In the operating mechanism of a talking machine, a speed governor having a friction disc, a brake therefor embodying a pivoted bell-crank lever, means for automatically applying the brake, and means for timing the application of the brake with respect to timing of a record. 80

3. In the operating mechanism of a talking machine having a traveling tone arm, a speed governor having a friction disc, a brake therefor embodying a pivoted bell-crank, means for automatically applying the brake, a setting adjustment therefor, and operating means carried by the tone arm for the application of the brake. 85

4. In the operating mechanism of a phonograph, a speed governor having a rotary friction disc axially moved by the governor, in combination with speed control and shut down brakes both engaged by the disc and a pivoted bell-crank lever carrying one of said brakes. 90

5. In the operating mechanism of a phonograph, a speed governor having a rotary friction disc axially moved by the governor, a stationary speed regulator brake adapted to be engaged by the disc and other brake mechanism adapted to be engaged by the disc for stopping and starting the operating mechanism and a pivoted bell-crank lever carrying one of said brakes. 100

6. In the operating mechanism of a phonograph, a speed governor having a friction disc, a stationary speed regulator brake therefor, a pivot about which the speed regulator is adjustable, and a scale for the regulator adjustable about the same pivot. 110

7. In the operating mechanism of a phonograph, a speed governor having a friction disc, a stationary speed regulator brake therefor, a pivot about which the speed regulator is adjustable, and an adjustable scale for the regulator. 115

8. In the operating mechanism of a phonograph, a speed governor having a friction disc, a fixed pivot, a scale adjustable about the pivot, a speed regulator brake lever mounted upon the pivot above the scale, a spring washer about the pivot compressed between the lever and scale, and a head on the pivot above the lever holding it to its duty. 125

9. In the operating mechanism of a phonograph. 130

- graph; a speed governor having a friction disc, a pivot, an arm pivotally mounted thereon and having an arcuate scale near its outer end, a speed regulator brake lever 5 mounted upon the pivot above and extending along the arm and above the scale having an opening to display the scale and contoured to provide an inwardly directed pointer above the scale to indicate the position of 10 the brake lever with respect to the scale, and means for maintaining the lever and scale in set positions.
10. In the operating mechanism of a phonograph, a driving shaft, a speed governor 15 of the spring and ball type, and means for locking the sliding ends of the springs from turning with respect to the shaft.
11. In the operating mechanism of a phonograph, a driving shaft, and a speed governor thereon of the spring-and-ball type having more than three spring-and-ball units 20 uniformly spaced around the shaft, a member movable on said shaft, and interengaging locking means for said member.
25. 12. In the operating mechanism of a phonograph, a driving shaft, and a speed governor of the spring-and-ball type having
- four spring-and-ball units balanced, each unit by a unit diametrically across from it and interengaging locking means holding 30 the unit-carrying means from turning with respect to the shaft.
13. In the operating mechanism of a phonograph, a driving shaft having a non-circular section at one end, a speed governor 35 of the spring and ball type about the shaft and a sliding collar with which the governor is connected surrounding the shaft moved by the governor and completing and sliding on the non-circular section of the shaft. 40
14. In the operating mechanism of a phonograph, a driving shaft, and a speed governor thereon of the spring-and-ball type having the balls flattened toward the springs and the outer contours of the balls corresponding generally to the figures generated by their revolution at average speed and means carrying said springs and locked 45 against turning with respect to said shaft but movable in the direction of the length of 50 the latter.

MANIE E. BURTON,
*Executrix of the Estate of Isaac F. Burton,
deceased.*
